HUMIDIFIER HEAD

Hugh Francis Hill, Fall River, Mass.

Application October 26, 1948, Serial No. 56,573

2 Claims. (Cl. 299—140)

1

This invention relates to humidifying apparatus, and more particularly to a new and improved atomizing head for mixing air and water under pressure to produce a spray.

One object of the invention is to provide a humidifying head which is much more efficient in use than those heretofore employed for like purposes.

Another object is to provide a device of the type specified having plural spray-nozzles arranged to direct the spray in different directions.

Another object is to provide a device of the type specified with an improved mixing chamber for mixing air or gas and liquid.

Another object is to provide a device of the type specified having a central pre-mixing chamber and an auxiliary final mixing chamber at the end of each spray nozzle.

Another object is to provide a device of the type specified embodying means for maintaining the liquid or water inlet unobstructed by, and the liquid free of, dirt and foreign particles.

Another object is to provide a device of the type specified in which the liquid valve-diaphragm is exposed to a cooling and cleaning action by the liquid.

Another object is to provide a tamper-proof device of the type specified in which adjustment of the liquid-valve pressure can be made only by dismantling the vaporizing head.

Further objects of the invention are set forth in the following specification which describes a preferred form of construction of the device, by way of example, as illustrated by the accompanying drawing. In the drawing:

Fig. 1 is a side elevational view of the present improved humidifying head with the spray from the plural spray-nozzles indicated graphically;

Fig. 2 is a top plan view of the device shown in Fig. 1;

Fig. 3 is a top plan view of the device illustrated with the upper cap or bonnet and valve-diaphragm removed and with one spray-nozzle shown in section;

Fig. 4 is a vertical axial sectional view of the device on line 4—4 of Fig. 3, showing the two spray-nozzles and their feed-ducts; and

Fig. 5 is a vertical axial sectional view of the device taken on line 5—5 of Fig. 3, showing the liquid inlet on the left and the air inlet on the right.

The present invention contemplates improvements in humidifier heads to render them more efficient in atomizing a liquid to form and eject a spray. The air and water are forced into an

2

inner, pre-mixing chamber under the influence of the respective pressures applied thereto and the resulting mixture fed through restricted passages into the outer mixing chambers, and thence to the atmosphere where it emerges as a more thoroughly mixed and efficiently atomized spray.

The invention further provides the advantage of double outlets to the final mixing chambers with two sprays projected in opposite directions from the single humidifier head. In general, the present improved head is designed for mixing air and water under pressure to produce a finely divided mist-like spray adapted for humidifying the interior of textile mills and other plants. However, other liquids and gases may be used with the atomizer for different purposes.

Referring to the drawing, the present improved humidifier head may be constructed with a cylindrical casing or body portion 10, a cap or bonnet 11 at the top, a bottom closure 12, and spray-nozzle tips 13 and 14. Each of the several caps or closures is screw-threaded for attachment to the main body portion or casing 10 and provided with a nut or other suitable formation to facilitate its assembly therewith and removal therefrom.

Suitable gaskets 15, 16 and 17 are inserted respectively between the bonnet 11, bottom closure 12 and spray-nozzle tips 13 and 14 and their seats in the casing 10 to seal the joints at the several points, see Figs. 3, 4 and 5. The main body portion or casing 10 may be of cylindrical shape and provided with a cylindrical recess forming a pre-mixing chamber 20 partly enclosed by the reduced threaded neck of the bonnet 11. Projecting diametrically from the casing 10 are two branch nozzles 21 and 22 having their terminal portions reduced in diameter and

screw-threaded to receive the spray-tips 13 and 14. The spray-tips or nipples 13 and 14 are set up against the gaskets 17 and dimensioned to provide chamber spaces 23 and 24 between the ends of the nozzles 21 and 22 and the end closure walls of the tips. The nozzles 21 and 22 are cored out or drilled to provide relatively small channels or ducts 25 and 26 leading from the pre-mixing chamber 20 into the open spaces 23 and 24 which form the auxiliary final mixing chambers for the air and water to further atomize the spray before it is projected through restricted openings 27 and 28 in the end walls of the tips 13 and 14, see Figs. 3 and 4.

The upper closure or bonnet 11 of the head is

provided with an axial bore 29 opening into a larger bore 30, counterbored at 31 to form a still further enlargement at its lower end for receiving a resilient cushion in the form of a washer 32. The washer 32 may be of synthetic rubber or similar material not subject to deterioration, being arranged to seat against the shoulder 33 formed by the counterbore 31 and serving as a gasket. In the upper axial bore 29 of the bonnet 11 is slidably mounted a plunger 35 formed with a shouldered enlargement or flange 36 at its lower end. A helical spring 37 surrounds the plunger 35 and is normally held under tension between the top wall of the bonnet 11 and the rim of the flange 36 at the lower end of the plunger. The plunger 35 is bored axially and threaded internally to receive the end of a screw-threaded spindle 39 carrying a disk-like valve-diaphragm 40 intermediate its ends. The valve-diaphragm 40 is provided with a lower hub-like projection 41 counterbored to receive a gasket 42 of rubber or other suitable material on its under side. The diaphragm 40 may be adjusted axially of the spindle 39 and locked in place by means of a threaded washer or nut 43.

The lower end of the spindle 39 extends down through a cylindrical opening or bore 44 in the main body of the casing 10 with a clearance around its sides as shown in Figs. 4 and 5. The orifice at the upper end of the bore 44 is surrounded by a tapered valve-seat 45 against which the resilient gasket 42 engages when the diaphragm 40 is forced downwardly by the tension of the spring 37 acting through the plunger 35. The lower end of the bore 44 opens into a flaring recess 47 debouching into a cylindrical chamber 48 formed in the bottom of the casing 10 which is closed by the lower cap 12. Held within the flaring recess 47 is a disk-like screen or filter 49 for restraining dirt and foreign matter from entering the bore 44. The recess 47 in the bottom of the casing 10 provides a clean-out chamber for removing any sediment of dirt or other particles in the water when the cap or closure is removed, see Fig. 4.

Water may be supplied to the head through a pipe 50 tapped into the side of the casing 10 with a pocket 52 at its end formed by the end of the drilled hole. A relatively small duct 53 leads from the pocket 52 down into the clean-out chamber 47 through which the water under pressure is forced and thence upwardly through the filter or strainer 49 and bore 44 to enter the pre-mixing chamber 20 as later more particularly explained.

Air may be supplied to the head through a pipe 55 tapped into the side of the casing 10 with a pocket 56 formed at its end by the end of the drilled hole. A duct 57 leads upwardly from the pocket 56 into the mixing chamber 20 as shown in Fig. 5. Referring now to Fig. 3, two other relatively small ducts 58 and 59 lead from the end of the pocket 56 outwardly through the nozzles 21 and 22 with their ends opening respectively into the auxiliary mixing chambers 23 and 24 within the ends of the spray-tips 13 and 14.

The method of operation of the complete device is explained as follows: The humidifier head is applied to use by connecting the casing or body member 10 with suitable supply pipes for air and water under pressure. Prior to its use the device is adjusted by turning the plunger 35 on the screw-threads of the spindle 39 to tension the spring 37 for holding the gasket 42 on the valve-diaphragm down against the seat 45 surrounding the orifice of the water inlet 44. The spring 75

37 is usually adjusted to prevent upward movement of the plunger 35 and valve-diaphragm 40 under a predetermined pressure, for example, twenty-three pounds to the square inch. It will be understood that the compressible washer 32 also applies some resistance to the upward movement of the valve-diaphragm 40 but this is relatively slight, not in any case equal to the tension of the spring 37. On the other hand, the compressible washer 32 acts as a gasket to seal off the bore 30 and prevent escape of air and water from the pre-mixing chamber 20 around the edges of the diaphragm 40.

With the device adjusted as above explained, air under the proper pressure is admitted into the pre-mixing chamber 20 from the inlet pipe 55 feeding through the duct 57 to raise the diaphragm 40 and lift its gasket off from the valve seat 45. Water is supplied by the pipe 50 to feed down through the duct 53 into the clean-out chamber 48. From the clean-out chamber 48 the water feeds upwardly through the strainer 49 and bore 44, when the valve is open, and into the pre-mixing chamber 20. Due to the eccentric relation of the duct 57 to the water valve at the seat 45 there is a tendency for the air to whirl or swirl around in the chamber 20 to insure its thorough mixing with the water. The water is thus finely divided and reduced to a dispersed condition as it is forced outwardly through the ducts 25 and 26 in the branch nozzles 21 and 22, whence it enters the auxiliary mixing chambers formed by the spaces 23 and 24 within the ends of the spray tips or nipples 13 and 14, see Fig. 3 of the drawing. It has been explained that the opening or chamber 56 at the end of the air pipe 55 also communicates with the auxiliary mixing chambers 23 and 24 by means of the ducts 58 and 59 opening therewith so that a further amount of air under pressure is received in these final mixing chambers to circulate therearound and augment the mixing operation by further saturation of the water with air. The atomized water is then forced through the restricted orifices 27 and 28 in the nipples 13 and 14 to emerge therefrom in a finely divided spray resembling a mist or fog. Through this novel method of pre-mixing and finally mixing the air and water much greater efficiency is attained than with other types of atomizers or humidifying devices to effectually prevent any escape of unatomized water. In other words, a maximum mixing proportion of water and air is effected by utilizing every ounce of air pressure.

The device is adjusted at the factory as before explained to cause a predetermined air pressure of twenty-three pounds per square inch to raise the diaphragm to open the water valve but upon a drop of three pounds in the pressure the water valve will be closed automatically by the spring 37 to shut off the water supply and arrest operation of the device. Thus, a positive opening and closing of the water valve is insured and in addition to the increased efficiency secured the device operates with other advantages as next explained. Dirt and other foreign particles in the water are prevented from passing into the mixing chambers by means of the screen or filter 49 and any sediment collecting in the clean-out chamber 48 may be disposed of by removing the bottom cap or closure 12. As a further cleaning provision, the spindle 39 through its sliding motion in the bore 44 has the effect to clean this water passage and prevent any collection of dirt therein liable to clog the action of the device. The valve-diaphragm 40 being con-

structed of metal overcomes the defects of previously-used flexible diaphragms of rubber or other resilient material liable to deterioration and the impingement of the water and air against its under side maintains the surface clean and free of any deposits.

It has been stated that the present improved humidifier head is furnished direct from the factory with its parts adjusted for efficient operation and the adjustment cannot be tampered with without dismantling the head by removal of its cap or bonnet 11. As a further improvement the device is extremely simple in design and construction, there being only one moving part comprising the combination of the plunger 35, diaphragm 40 and spindle 39. The device is therefore much more economical to manufacture, less liable to derangement of its operating parts and getting out of order, and more durable in use over long periods of time. Practically the only part that requires replacement is the screen or filter 49 which may be readily removed for cleaning or replaced at small cost without disturbing the adjustment of the operating elements of the device.

The improved device is herein shown and described as embodied in a preferred form of construction, but various modifications may be made in the structure and arrangement of its parts without departing from the spirit or scope of the invention. For example, a copper bellows of usual form may be substituted for the resilient gasket 32 to operate in the same manner for the same purpose. Further modifications in the structure and arrangement of the device may be made within the scope of the invention as expressed in the following claims and therefore, without limiting myself in this respect, I claim:

1. A humidifier head comprising a casing provided with a central pre-mixing chamber, a water passage leading into said chamber, a clean-out chamber at the supply end of the water passage, an air inlet communicating with the pre-mixing chamber, a removable cap for closing the clean-out chamber, a diaphragm slidable in the pre-mixing chamber and provided with means for closing the end of the water passage in said chamber, a spindle projecting downwardly from the diaphragm and through the water passage, a plunger having a screw-thread-

50

- ed connection with the upper end of said spindle, a spring surrounding the plunger and acting to slide the diaphragm to close the end of the water passage, a nozzle on the casing, a duct leading from the pre-mixing chamber through the nozzle, an auxiliary mixing chamber at the end of the nozzle, a nipple on the nozzle having a constricted orifice, and a duct leading directly from the air inlet to the auxiliary mixing chamber at the end of the nozzle.
2. A humidifier head having a main casing comprising a lower section formed with a nozzle thereon, an upper hollow bonnet having a screw-threaded connection with said casing section to provide a central mixing chamber, a clean-out chamber at the bottom of the lower section, a cap screw-threaded to the bottom of said lower section for closing the clean-out chamber, a water passage leading from the clean-out chamber upwardly into the mixing chamber, a screen at the lower end of said water passage, a valve-seat at the upper end of said water passage, a valve-diaphragm slidable in the mixing chamber and engageable with the valve-seat to prevent ingress of water into the mixing chamber, a plunger slidable in a bearing in the bonnet and connected to slide the valve-diaphragm to close the valve opening, resilient means for sliding the plunger, an air inlet communicating with the mixing chamber, a water supply inlet communicating with the clean-out chamber below the screen, a duct leading from the mixing chamber to the end of the nozzle, and a nipple on said nozzle formed with a constricted orifice through which atomized water is projected in a spray.
